UNITED STATES PATENT OFFICE.

ISAAC HALL, OF BOSTON, MASSACHUSETTS.

MECHANISM FOR CUTTING AND PRICKING THE SOLES FOR BOOTS AND SHOES.

SPECIFICATION forming part of Letters Patent No. 243,069, dated June 21, 1881.

Application filed April 4, 1881. (No model.)

To all whom it may concern:

Be it known that I, ISAAC HALL, of Boston, county of Suffolk, and State of Massachusetts, have invented a new and useful Improvement 5 in Mechanism for Cutting and Pricking the Soles of Boots and Shoes, of which the following description, in connection with the accompanying drawings, is a specification.

This invention relates to an apparatus for 10 cutting out and pricking the soles of boots and shoes; and it consists, essentially, of a sole-cutting die and ejector therein, provided with a series of holes about its edge, combined with a series of fixed awls located to 15 extend through the said holes, as the ejector is forced back into the die, against springs located within the said die and prick holes in the sole as it is being cut from the side of leather, the ejector discharging the pricked 20 sole as the die is lifted above the side of leather. The normal position of the ejector is at the level of the cutting-edge of the die and below the points of the awls.

Figure 1 is an under-side view of a sole cutting and pricking apparatus made in accordance with my invention, and Fig. 2 a longitudinal section thereof.

Referring to the drawings, A represents a sole-cutting die of usual construction, it having 25 a cutting-edge of the form desired to give to the sole to be cut from the side of leather. The cutting-die has a back plate, b, connected therewith by means of screws a, and, as herein shown, the same screws a secure within the die the awl-holding plate c, provided with a series of awls, c², arranged at a uniform or proper distance from the cutting-edge of the cutting-die, and having their points extended down almost to the lower edge of the said 35 cutting-die, as shown in Fig. 2, the lower ends of the said awls being extended into the series of holes d² in the ejector-plate d. This ejector-plate is carried by the headed bolts or rods f, 40 extended upward through springs h, placed within the die, as represented in Fig. 2, the action of the said springs keeping the heads of the rods f g seated upon the plate c. The 45 normal position of the ejector-plate is as shown in Fig. 2; but when the die is forced down

upon the side of leather to cut the sole therefrom, the ejector-plate rises or is forced upward within the die in the direction of the arrow as the cutting-edges of the die pass through the side of leather, the upper ends of rods f g at such time passing upward through holes b⁴ b⁵ 55 in the plate b; but as soon as the die A is lifted from the side of leather the springs h immediately expand and move the ejector outward to discharge the sole from the die and strip it from the awls c², for as the cutter was 60 forced through the side of leather and the ejector was forced up into the die the ends of the awls were permitted to come in contact with the sole-shaped piece of leather within 65 the die and punch a series of holes through the said sole all about its edge. These holes will receive the nails or fastenings employed to secure the outer sole upon the lasted shoe, thus doing away with the trouble of pricking the nail-holes by a hand-operated awl. 70

I am aware that dies capable of cutting out pieces of leather have been provided with a series of punches to punch holes through the said leather, and that an ejector has been contained within such a die; but the ejector has 75 normally been held elevated within the die, the pieces cut out by the die accumulating therein, and to eject the said pieces the ejector, drawn into the die by springs, has been forced outward from the die by hand. 80

I am also aware that dies capable of cutting out pieces of leather have been provided with short awls not guided at their lower ends, and with means for casting off the punched and cut sole, consisting of stationary rods which 85 work through holes in the die-plate and come in contact with the sole and push it out of the die after the cutting and pricking has been accomplished; but in such contrivance there was no ejector or pressing-surface to bear upon the entire surface of the sole while being cut and punched. 90

I claim—

The sole-cutting die A and the series of awls c² and awl-holding plate, combined with the 95 perforated ejector, provided with holes for the passage of the awls, and with the springs h, to normally retain the ejector substantially or

just below the level of the edge of the cutting-blade and beyond the points of the awls, to shield them, the ejector yielding or moving back with the die for a distance equal to the thickness of the sole being cut, and then immediately being moved outward by the springs as the die is raised, substantially as described.

In testimony whereof I have signed my name to this specification in the presence of two subscribing witnesses.

ISAAC HALL.
